SECTIONAL WALK-IN COOLER

Arthur A. Anderson, St. Paul, Minn., assignor, by mesne assignments, to Whirlpool-Seeger Corporation, St. Joseph, Mich., a corporation of Delaware

Application May 3, 1948, Serial No. 24,707

1 Claim. (Cl. 189—2)

My invention relates to an improvement in sectional walk-in cooler and deals particularly with a manner of connecting these sections together.

Walk-in coolers are preferable over chest type coolers in many locations. For example in meat markets, and similar stores, a chest type cooler is inconvenient to use, particularly where large sections of meat and other products are being stored. Even in homes where coolers are used, the walk-in cooler supports the cooled or frozen food more accessibly than other types of coolers. However, in the past it has been usually necessary to build such a cooler permanently into the store or home, as a walk-in cooler is ordinarily of too large dimensions to be moved through doorways and the like.

An object of the present invention lies in the provision of a cooler formed in sections and in designing these sections so that they may be readily attached and detached. As a result the cooler may be moved to a desired location in sections and assembled to produce a cooler of the desired dimensions.

A feature of the present invention lies in the provision of a sectional cooler being formed of a series of sections which are detachably connected together. Each section includes inner and outer panels or coverings which are marginally connected by breaker strips so that a minimum of heat will be conducted through the wall. Latch means are provided which are placed at desired intervals to connect the various sections together. This latch means locks adjacent sections together and holds them firmly in place as long as the cooler remains assembled. However, if desired the latch means may be released so that the sections may be detached one from another so that the cooler may be moved to a different location. The detachability of the sections also is important because of the fact that by this means the cooler may be enlarged if desired, or changed in shape by adding additional sections or by changing the relationship thereof.

A feature of the present invention lies in the provision of a latch having a pivotally supported latch arm movable into extended or retracted position. The latch arm is so constructed that in one extreme position it will extend freely through an aperture in the adjacent section. In its other extreme position the projecting hook end thereof will engage a wall of the adjacent section and clamp the two sections firmly together.

An added feature of the present invention lies in the provision of a latching means including a hook ended latch arm and a pivotally supported crank arm to which the latch arm is pivotally secured. Upon swinging the crank arm in one direction, the latch arm will be projected a substantial distance through an edge of the section on which it is mounted and the hook end of this latch arm will be raised. By swinging the crank arm in the opposite direction the hook end of the latch arm will be lowered and will be moved toward the edge from which it projects.

2

An added feature of the present invention lies in the provision of a latch mounted to extend through the breaker strips connecting inner and outer refrigerator linings of two adjacent sections and clamping these sections together in edge abutting relationship.

These and other objects and novel features of my invention will be more clearly and fully set forth in the following specification and claim.

In the drawings forming a part of my specification:

10 Figure 1 is a side elevational view of a sectional cooler showing the construction thereof.

Figure 2 is a top plan view of the sectional cooler of Figure 1, a portion of the wall being broken away to show the construction thereof.

Figure 3 is a sectional view through the edges of two adjacent sections showing the latch mechanism.

Figure 4 is a sectional view through the adjacent sections, the position of the section being indicated by the line 4—4 of Figure 3.

Figure 5 is a sectional view through the lower end of a side wall section showing the manner in which the side walls are connected to the base section.

Figure 6 is a sectional view through the upper end of a wall section and a portion of a top section showing the manner in which these sections are connected together.

Figure 7 is a sectional view showing the connection between two adjacent top sections.

30 The cooler A is only typical of various types and shapes of coolers which may be used. This cooler A is shown as including a central rear wall section 10, two rear corner sections 11 and 12. The cooler includes one or a series of side wall sections 13 and front corner sections 14 similar to the rear corner sections 11 and 12. A door 15 may be mounted between the front corner sections 14 to complete the wall structure.

35 The cooler A includes a floor 16 which is illustrated as being formed in sectional parts. The top of the cooler is closed by a rear end section 17, one or more center top sections 19 and a front top section 20. The front and rear top sections 17 and 20 may be identical in form and reversed in position.

40 The typical floor section 18 may be formed in any suitable manner, but is shown as including a series of cross beams 21 which are provided with channel shaped bearing caps 22 at the upper and lower extremities. An outer metallic covering 23 includes a bottom panel 24 which is turned up marginally to provide side wall flanges 25 and inturned marginal edge flanges 26. An inner panel 27 of metal or the like is supported by the capped beams 21 in spaced relation to the inturned flanges 26. A composition floor 29 overlies the inner panel 27 and over the various floor sections and forms a flooring within the cooler.

45 The floor section thus constructed, as well as the other sections forming the floor, is provided with a raised guide rail 30 extending marginally thereabout as best illustrated in Figure 5. This guide rail 30 includes a central elevated portion 31, downwardly and outwardly inclined side wall flanges 32 and 33, and inturned bearing flanges 34 and 35. The rail 30 is held in place by fastening means 36 of any suitable type.

50 Each wall section is constructed with an inner panel 37, and an outer panel 39 usually of metal or the like. The inner panel 37 is provided at its lower edge with an inturned flange 40 which continues to form an upwardly inclined flange 41 and an inwardly extending marginal flange 42. The outer panel 39 is also provided at its lower edge with an inturned flange 43. An upwardly and inwardly inclined flange 44 is connected to the inner edge of the flange 43 and a marginal flange 45 is formed on the flange 44. The flanges 42 and 45 are arranged

in opposed coplanar relationship and are connected together by breaker strips 46 of a material of relatively low heat conductivity.

To assist in holding the inner and outer panels in proper relation, a breaker strip 47 also lies against the inner surfaces of the flanges 42 and 45 and rests marginally on spacing blocks 49. Fastenings 50 connect the strips 46 and 47 to the flanges 42 and 45. Gaskets 51 and 52 are secured to the inturned flanges 40 and 43 as also illustrated in Figure 5. These gaskets are secured to the flanges with rubber cement.

Each side wall section is formed with one edge which forms the female portion of a joint or connection, while the other edge thereof forms the male portion of the connection. In Figure 3 of the drawings I disclose a section through the edges of adjacent wall sections to show the manner in which these wall sections interfit together. The male portion of the connection is formed by bending inwardly a vertical edge of the outer panel 39 to form a flange 55 which merges into an inclined flange 56 and terminates in an inturned marginal flange 57. The inner panel 37 is also bent inwardly along a corresponding vertical edge to form an inturned flange 59 which merges into an inclined flange 60 terminating in an inturned marginal flange 61. The flanges 57 and 61 are arranged in co-planar relationship and a breaker strip 62 connects these flanges. Metal screws or other fastening means 63 are used to hold the breaker strip 62 in place. An additional breaker strip means 64 lies inwardly of the co-planar flanges 55 and 59 and is secured thereto by metal screws 65 or other suitable means.

The female portion of the connection is provided along the opposite vertical edge of each section. The outer panel 39 is bent inwardly to form an inturned flange 66 which merges into the inclined flange 67 and terminates in the inturned marginal flange 69. The inner panel 39 is also bent outwardly to form a flange 70 which merges into an inclined flange 71 and terminates in a marginal flange 72. A breaker strip 73 lies outwardly of the opposed coplanar marginal flanges 69 and 72 and is secured thereto by metal screws 74 or other suitable means. Breaker strip means 75 also lie inwardly of the flanges 69 and 72 and is held in place by the screws 74. The side edges of this breaker strip means 75 lies against spacing strips or blocks 76 and is secured thereto in any suitable manner.

The top panels dovetail into the side wall sections as best illustrated in Figure 6 of the drawings. It will be noted that the top marginal edges of the outer side wall panels 39 are turned inwardly to provide an inturned flange 77 which merges into a downwardly and inwardly inclined flange 79 and terminates in a marginal inturned flange 80. The inner wall panel 37 is likewise provided with an outwardly turned flange 81 which merges into the downwardly and outwardly inclined flange 82 and terminates in an outturned marginal flange 83. A breaker strip 84 lies above the opposed coplanar flanges 80 and 83 and a second breaker strip 85 lies below these flanges. Screws 86 or other suitable means connect the breaker strips to the flanges 80 and 83. Spacer blocks or strips 87 are interposed between the marginal edges of the lower breaker strip 85 and the flanges 77 and 81.

The top sections are also provided with marginal male joint portions which fit into the female joint portions at the upper edges of the side wall sections. The top sections include a top panel 89 which bends downwardly along outer edges of the section to form outer edge walls 90. The walls 90 are provided with inturned marginal flanges 91 which merge into downwardly and inwardly inclined flanges 92 and terminates in inwardly turned marginal flanges 93. The inner or under panel 94 of each top section is provided adjacent its outer edges with a downwardly and outwardly inclined flange 95 and terminates in an outturned flange 96. The flanges

93 and 96 are arranged in co-planar relation and a breaker strip 97 connects these flanges and is secured thereto by screws 99 or other suitable fastening means. An inner breaker strip 100 overlies the flange 91 and the upper surface of the panel 94 and is secured thereto by suitable means 101.

The above described joint obviously only extends about the outer walls of the top sections. The adjacent walls of the top sections are provided with male and female connections of the type previously described as extending along a vertical wall section. The rear wall section 17 thus provides a joint of the type described above along three marginal edges, while the fourth edge is connected along the male and female connection 102 illustrated in detail in Figure 7 of the drawings.

The top panel 89 is provided with a downwardly turned flange 103 merging into a downwardly inclined flange 104 and terminating in a down-turned flange 105. The lower panel 94 is provided at its corresponding edge with an upturned flange 106 which merges into an inclined flange 107 and terminates in an up-turned flange 109. The flanges 105 and 109 are engaged against opposite surfaces of these flanges and breaker strips 110 and 111 connect these flanges and are secured thereto in any suitable manner. The cooperating edge of the next adjacent section has its top panel 89 bent downwardly to form the flange 112 which merges into the inclined flange 113 and terminates in the down-turned flange 114. The bottom panel 94 has a corresponding up-turned flange 115 which merges into an inclined flange 116 and terminates in a marginal flange 117. The breaker strip 119 lies outwardly of the flanges 114 and 117 and is secured thereto. The breaker strip 120 lies inwardly of the flanges 112 and 115 and is secured marginally thereto.

The various sections are connected together along their meeting edges by a latch apparatus best illustrated in Figures 3 and 4 of the drawings. Such latch devices are supported in spaced relationship about the marginal edges of all of the sections. As all of these latch devices are identical in form and construction only one such device will be described in detail. As has been described previously the various sections include inner and outer panels which are separated by inner and outer breaker strips. The inner breaker strip, such as the strip 64 of Figures 3 and 4 of the drawings acts as a support for a pair of spaced parallel brackets 120 and 121 having anchoring flanges 122 and 123 thereupon which lie inwardly of the breaker strip 64 and are secured thereto by screws 124 or other attaching means. A pivot 125 extends through these plates 120 and 121 and is provided with a multi-sided shank 126 thereon which extends toward the inner panel 37 of the section. The end of the square shank 126 forms a shoulder 127 which abuts against the plate 121 and holds this pivot from axial movement in one direction. A crank arm 129 is mounted upon the pivot 125 between the plates 120 and 121. The end of the pivot opposite the square shank 126 projects through the plate 120 and a cotter pin 127 or other suitable device extends through this shank to hold the pivot from axial movement.

A latch arm 130 is pivotally connected at 131 to the crank arm 129. The latch arm 130 has an unusual outline shape best illustrated in Figure 4 of the drawings. This latch arm includes a downwardly projecting arm end 132 which is connected to a laterally extending arm portion 133 which terminates in a downwardly facing hook end 134. The arm portion 133 includes an upwardly extending hump 135 spaced from the hook end 134 and a downwardly projecting bulge or hump 136 somewhat closer to the pivoted end 132. The arm is notched between the pivoted end 133 and the hump 136 so as to extend above the pivot 125 in locked position of the latch.

The latch arm 130 extends through an aperture 136 in the breaker strip 64 and through a substantially aligned aperture 139 in the breaker strip 62. The projecting hook

end 134 is likewise designed to extend through apertures such as 140 and 141 in the breaker strips 73 and 75 respectively.

The aperture 137 in the breaker strip 64 and the adjoining aperture 142 in the latch base clip 143 controls the position of the latch arm in the operation thereof. The hook end 134 of the latch arm tilts upwardly as this latch arm projects farther through the apertures 137 and 142 and tilts downwardly as the latch arm is retracted into these apertures. As indicated in Figure 4 of the drawings when the arm 129 is pivoted in a counter-clockwise direction from the full line position illustrated the right hand end of the latch arm 130 is raised slightly and then begins to move outwardly through the apertures 137 and 142. The hump 136 soon strikes against the lower edge of the aperture 142 tending to raise the hook end of the latch. Thus as the latch arm moves toward projected position the hook end swings upwardly until the arm 129 reaches a position at approximately ninety degrees from the full line position. Further rotation of the arm 129 in a counter-clockwise direction swings the pivoted end 132 of the latch arm 130 downwardly so as to tilt the latch upwardly until the hook end 134 thereof is entirely free of the portion of the adjacent section which it engages. While in this tilted position the latch may be removed from the adjacent section by moving the two sections apart.

It will be noted that as the arm 129 is rotated in a clockwise direction the pivoted end 132 of the latch arm is raised slightly and then begins to move toward retracted position. After the hump 136 has been disengaged from the lower edge of the aperture 142, the hump 135 engages the upper edge of this aperture to urge the hook end 134 downwardly. Thus the engagement of this hook end with the lip 143 of the metallic reinforcing frame 144 of the adjacent section portion is insured.

It will be noted that the hook end is shaped to engage below the lip 143 of the reinforcing frame 144 encircling the aperture 140 of the cooperable section. In latched position of the latch arm it will be noted that the pivot 131 extends beyond a straight line between this hook end 134 and the pivot axis 125. As a result the end of the latch goes beyond the center line between the end 134 and pivot 125 so as to insure permanent engagement of the latch until the same is manually disengaged.

An opening 145 is provided in the inner panel 37 in alignment with the square shank 126 of each latching means, this opening being normally closed by a closure plate 146 having spring prongs 147 thereon. A socket wrench of a suitable type is engageable through this aperture 145 for rotating the pivot 125. Thus in assembling the various sections the wrench is inserted through the adjacent opening 145 of each latch means and the latch is pivoted from projected position into retracted position, thus clamping the sections together at spaced points about their periphery.

In accordance with the patent statutes, I have described the principles of construction and operation of my sectional walk-in cooler, and while I have endeavored to set forth the best embodiment thereof, I desire to have it understood that obvious changes may be made within the scope of the following claim without departing from the spirit of my invention.

I claim:

A sectional cooler including a pair of wall sections disposed in an end to end relation, each wall section comprising inner and outer panels, the inner and outer panels of one wall section having inturned flanges, recessed marginal flanges substantially parallel to said inturned flanges and inclined flanges connecting with said inturned and marginal flanges, said several flanges forming a female end, breaker strip means on each side of said marginal flanges, said strip means being apertured and the inner strip means carrying a latch clip, the inner and outer panels of said other wall section having inturned flanges, marginal flanges received by said female end of said first mentioned section, said marginal flanges being substantially parallel to said inturned flanges and inclined flanges connecting with said last mentioned inturned and marginal flanges, breaker strip means carried by said last mentioned marginal flanges and breaker strip means carried by said last mentioned inturned flanges, said breaker strip means being apertured, bracket means supported by said last mentioned breaker strip means, a shank rotatably carried by said bracket means, an arm mounted on said shank for rotation therewith, a latch arm pivotally mounted to said first mentioned arm, said latch arm extending through the apertures of said various strip means, and having an end engageable with said latch clip, and compressible gasket means interposed between the opposed faces of the respective inturned flanges, whereby rotation of said shank in one direction will cause clamping of said sections in said end to end relation with the concomitant compression of said gasket means.
